FLUID CONTROL FOR FLUID OPERATED PRESSES

Clifton S. Malott, Jr., Norwood, Ohio, assignor to The American Laundry Machinery Company, Norwood, Ohio, a corporation of Ohio

Application January 21, 1935, Serial No. 2,693

8 Claims. (Cl. 121—38)

This invention relates to improved control mechanism for a power operated pressing machine of the type generally used in laundry and garment work.

6 An object of the invention is to provide a fluid motor for closing a pressing machine, control valves therefor normally in press open position, fluid power means for moving these valves to press closed position and for holding them there, and 10 two fluid supply circuits for this power means, one operator operated which actuates the power means to move the valves to press closed position and if maintained a sufficient length of time establishes the second circuit for the power means 15 which is self-maintaining, thus permitting the release of the operating manuals.

My invention also contemplates the provision 20 of a unitary structure including the fluid motor, valves, power means and time delay mechanism above described in a unit suitable to be installed upon a foot power press and requiring the provision only of suitable manuals for its application to a pressing machine to convert it to a full power operated machine.

25 My invention also contemplates certain novel structure for carrying out the above objects and provisions as will more clearly appear in the accompanying drawings and specification and the essential features will be summarized in the 30 claims.

35 In the drawings, Fig. 1 is an end elevation partly in section showing a pressing machine embodying my invention; Fig. 2 is a diagrammatic layout of the control circuits for the machine of Fig. 1; while Fig. 3 is a view similar to Fig. 2 showing the parts in an actuated position.

The pressing machine illustrated comprises a 40 frame 10 supporting a pressing bed 11. On a portion of the frame is pivotally mounted a head lever 12 which carries a pressing head or chest 13 which is adapted to coat with the bed 11. For moving the head, I have provided toggles 14 connected between the rear end of the head lever and the frame, a spring 15 normally biases these 45 toggles to broken position. For closing the press I have provided a motor 16 suitably mounted on the frame having its piston rod connected to the toggle knuckles at 17 so that a power stroke of motor 16 closes the press.

50 My novel control mechanism is shown in Fig. 2 in which the motor 16 is shown as having a cylinder 18 equipped with a piston 19 whose piston rod 20 is connected to the toggles 14 as previously described. A valve casing 21 houses the control valves for motor 16 which, in the

present instance, comprise a normally closed inlet valve 21a and a normally open outlet valve 21b which are mounted on a common sleeve 21c which is carried by a stem 21d connected to power means for actuating the valves. The 5 sleeve 21c is held between a shoulder 21e on the stem 21d and a spring 22 which is held between the sleeve 21c and a collar 23 which is rigid with the stem. This forms a yieldable connection which permits movement of stem 21d after valve 10 21b has been closed and valve 21a has been opened. Valve casing 21 communicates by a suitable flow and exhaust passageway 24 with cylinder 18 and the casing is provided with a port 25 for communication with a supply of motive 15 fluid and another port 26 for exhaust of motive fluid to the atmosphere. The motor control valves are biased in press closed position by a spring 27 which is compressed between casing 21 and a collar 28 which is rigid with stem 21d. 20

I provide fluid power means for actuating the motor control valves and in the form illustrated this comprises a pair of aligned cylinders 29 and 30 which are provided with pistons 29a and 30a respectively, both pistons being mounted on the 25 valve stem 21d.

A press closing circuit supplies power to cylinder 29 as follows:

30 A combined flow and exhaust conduit 31 communicates with cylinder 29 and the lower face of piston 29a and the flow of fluid in this conduit 31 is controlled by two spaced safety manuals 32 and 33 controlling inlet and outlet valves which are housed in casings 32 and 33. Each casing houses a normally closed inlet valve 32a, 33a and a normally open outlet valve 32b, 33b which are mounted on a common stem 32c, 33c for actuation by a manual 32d, 33d. These valve casings are connected in series by a conduit 34 and valve casing 32 communicates by a conduit 35 with a 35 source of motive fluid 36. The stroke of piston 29a when so supplied with power moves valves 21a and 21b to their operated position with the inlet valve open and the outlet valve closed. Power is 40 then supplied to motor 16 through conduit 36, 45 port 25, valve 21a and passageway 24.

Means is provided for delaying the establishment of a maintaining circuit for holding valves 21a and 21b in their operated position until the pressing members have had time to reach safely 50 closed position. This is for the purpose of compelling the operator to maintain both hands in a safe position, that is with one on each of the manuals 32d and 33d, until the press is safely closed. This means comprises mechanism for 55

establishing the maintaining circuit for cylinder and piston 30, 30a which is actuated upon movement of the yieldable connection between collar 23 and sleeve 21c and this movement is delayed by a timing device. The maintaining circuit for motor 30, 30a comprises a flow and exhaust conduit 37 which communicates with cylinder 30 and the lower face of piston 30a. This conduit leads to a valve casing 38 which houses a normally open inlet valve 38a and a normally closed outlet valve 38b which are mounted on a common stem 38c for actuation by a manual 38d. Leading from casing 38 and communicating with conduit 37 through normally open inlet valve 38a is a conduit 39 which communicates with a valve casing 40 in which are mounted a normally closed inlet valve 40a and a normally open outlet valve 40b which are mounted on a common stem 40c. The inlet valve end of casing 40 communicates with the fluid pressure source 36'. Actuation of stem 40c is by means of an arm 41 which is rigidly mounted on stem 21d. Contact between arm 41 and valve stem 40c is controlled by a timing device 42 which delays the taking up of the previously described yieldable connection upon movement of stem 21d. This timing device is shown as comprising a dash pot which, if desired, may be carried by a bracket 43a which is rigidly connected with the motor 16 and its associated valve structure. The dash pot 30 may be provided with a piston 43 rigid on the lower end of stem 21d. This piston has a port 44 extending therethrough which is closed by a flapper valve 45 on the up stroke of the piston but which permits free flow through the port 44 on the down stroke of the piston. The upper and lower ends of the dash pot communicate through a bypass 46 in which the flow is restricted by an adjustable needle valve 47. It is thus possible to nicely time the action of the dash pot.

With the parts in the position of Fig. 1, the operation of the device is as follows:

The operator arranges the lay of the work on bed 11 and actuates manuals 32d and 33d. Fluid then flows through the press closing circuit 36, 35, 32a, 34, 33a, 31 to the lower face of piston 29a. This piston moves upwardly, opening valve 21a and closing valve 21b. This establishes the power circuit for motor 16 through 36, 25, 21a and 24. If manuals 32d and 33d are maintained a sufficient length of time, piston 29a will continue to travel upwardly until the yieldable connection is taken up in stem 21d which will be delayed by the action of dash pot 42. Upon sufficient movement of this connection arm 41 contacts stem 40c which closes valve 40b and opens valve 40a. This establishes the following maintaining circuit: 36', 40a, 39, 38a, 37 to the lower face of piston 30a. The pistons 30a and 29a are thus maintained in their uppermost position and the press remains closed.

The operator may then release manuals 32d and 33d which will evacuate cylinder 29. To open the press, manual 38d is actuated which closes valve 38a and opens valve 38b which will evacuate cylinder 30. Spring 27 then returns stem 21d and all of its associated parts to the position of Fig. 2 which releases stem 40c permitting the spring in casing 40 to return those valves to the position of Fig. 2. Pressure in motor 16 is thus exhausted and spring 15 opens the press.

While the parts of my control mechanism need not be arranged as shown in Fig. 2, there is an advantage in so arranging the parts in a unitary structure. It will be noted that the motor 16 and its actuating valves and the power means for actuating those valves and the valves in casing

40 for providing a maintaining circuit for motor 16 and the dash pot 42 for delaying the establishment of the maintaining circuit are all rigidly connected together, and this makes it possible to mount such a unitary assembly on a foot power press which then requires only the connecting up of the fluid lines and the placing of suitable manuals on the pressing machine table to convert a foot power press to a completely power operated pressing machine with two-hand control. 10

What I claim is:

1. In a pressing machine, a pair of coacting relatively movable pressing members, operating means therefor including a fluid actuated motor and mechanism operated thereby for relatively moving said members for causing an ironing operation therebetween, conduit means for the supply and exhaust of motive fluid to and from said motor and including a normally closed inlet valve and a normally open outlet valve, an actuator movable to press-closing position to open said inlet valve and to close said outlet valve, said actuator having a connection permitting additional movement beyond said press-closing position, fluid actuated power means for moving said actuator, a timing device controlling said additional movement of said actuator, two fluid supply circuits for said power means, one of said circuits including an operator-operated control member, the other of said circuits including a valve normally preventing the effective flow of motive fluid therein, and an operative connection between said actuator and said last-named valve and effective to move the latter to flow establishing position upon completion of the action controlled by said timing device. 30

2. In a pressing machine, a pair of coacting relatively movable pressing members, operating means therefor including a fluid actuated motor and mechanism operated thereby for relatively moving said members for causing an ironing operation therebetween, conduit means for the supply and exhaust of motive fluid to and from said motor and including a normally closed inlet valve and a normally open outlet valve, an actuator movable to press-closing position to open said inlet valve and to close said outlet valve, said actuator having a connection permitting additional movement beyond said press-closing position, fluid actuated power means for moving said actuator, a dash-pot operatively connected with said actuator for delaying said additional movement thereof two fluid supply circuits for said power means, one of said circuits including an operator-operated control member, the other of said circuits including a valve normally preventing the effective flow of motive fluid therein, and an operative connection between said actuator and said last-named valve effective upon completion of said additional movement of said actuator for moving said last-named valve to flow establishing position. 50

3. In a pressing machine, a pair of coacting relatively movable pressing members, operating means therefor including a fluid actuated motor and mechanism operated thereby for relatively moving said members for causing an ironing operation therebetween, conduit means for the supply and exhaust of motive fluid to and from said motor and including a normally closed inlet valve and a normally open outlet valve, an actuator movable to press-closing position to open said inlet valve and to close said outlet valve, said actuator having a connection permitting additional movement beyond said press-closing position. 70

tion, fluid actuated power means for moving said actuator to press-closing position and therebeyond, a fluid supply circuit for said power means including operator-operated control means, a timing device operatively connected with said actuator for controlling the said additional movement thereof, fluid actuated holding means for maintaining said valves in press-closing position, a fluid supply circuit for said holding means, and means actuated by said actuator upon completion of its additional movement for establishing said last-named supply circuit.

4. The combination of claim 3, in which said operator-operated control means in said fluid supply circuit for said power means comprises spaced valves arranged to be operated simultaneously to provide an effective flow of motive fluid in said circuit.

5. The combination of claim 3, in which said fluid supply circuit for said holding means includes a valve casing, a normally open inlet valve and a normally closed outlet valve in said casing, said outlet valve communicating with the atmosphere, and a manual for operating said valves to close the inlet and to open the outlet, whereby said holding means may be released.

6. In a pressing machine, a pair of coacting relatively movable pressing members, operating means therefor including a fluid actuated motor and mechanism operated thereby for relatively moving said members for causing an ironing operation therebetween, conduit means for the supply and exhaust of motive fluid to and from said motor and including a normally closed inlet valve and a normally open outlet valve, fluid actuated power means movable to press-closing position for opening said inlet valve and closing said outlet valve, means for timing the movement of said power means, two fluid supply circuits for said power means, one of said circuits including

an operator-operated control member, the other of said circuits including a valve normally preventing the effective flow of motive fluid therein, and said power means having an operative connection with said last-named valve arranged to move the said valve to flow-establishing position upon completion of the movement of said power means controlled by said timing means.

7. Power means adapted to be mounted upon a foot-operated pressing machine comprising, as a 10 unitary assembly, a cylinder and piston motor for connection to press operating mechanism, inlet and outlet valves for the supply and exhaust of motive fluid to and from said cylinder, a passageway communicating with said cylinder and valves, 15 passageways for connecting said inlet valve with a fluid supply and said outlet valve with the atmosphere, an actuator for moving said valves into supply position, fluid power means for holding said valves in supply position, and a timing 20 device for delaying initiation of the holding action of said last named power means.

8. Power means for operating a pressing machine comprising, a cylinder and piston motor, a valve casing housing inlet and outlet valves for 25 the supply and exhaust of motive fluid to and from said cylinder, said casing including a passageway communicating with said cylinder and ports for communication with a fluid supply and with the atmosphere, an actuator for moving 30 said valves, fluid power means for moving said actuator, a timing device for delaying the movement of said fluid power means, a valve adapted for connection in a maintaining circuit for said fluid power means, and an operative connection 35 between said fluid power means and said last named valve effective for valve operation upon completion of the delayed movement of said fluid power means.

CLIFTON S. MALOTT, JR. 40
